UNITED STATES PATENT OFFICE.

LOULA S. REEVES, OF WARREN, OHIO.

TOY FIGURE.

1,273,538.

Specification of Letters Patent.

Patented July 23, 1918.

Application filed October 7, 1915. Serial No. 54,506.

To all whom it may concern:

Be it known that I, LOULA S. REEVES, a citizen of the United States, and a resident of Warren, county of Trumbull, and State of Ohio, have invented a new and useful Improvement in Toy Figures, of which the following is a specification, the principle of the invention being herein explained and the best mode in which I have contemplated 10 applying that principle, so as to distinguish it from other inventions.

The present improvements relate to the construction of a toy figure with particular regard to the structure and attachment of 15 the head and the limbs in order to firmly secure these parts to the body, and also to provide for free movement of the parts with respect to the body. To the accomplishment of the foregoing and related ends, 20 said invention, then consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

30 Figure 1 is a front view of the figure; Fig. 2 is a transverse vertical section through the head and upper part of the trunk; Fig. 3 is a horizontal section on the line 3—3, Fig. 1; Fig. 4 is a section similar to that 35 shown in Fig. 2 but of the lower part of the trunk; Fig. 5 is a perspective view of the inside of the bottom of the head, and Fig. 6 is an enlarged, partial section through the 40 head, the plane of the section being indicated by the line 6—6 in Fig. 2.

Referring to Fig. 1, the trunk 1 of the figure, or doll as here shown, is constructed of a covering 2 of waterproofed cloth or fabric which is stuffed with wool, cotton, or 45 sawdust, or similar material, and is provided at the top with a reinforcing plate 3 beneath the covering fabric, this reinforcing plate being provided with a shallow circular recess 4. This reinforcing plate 3 is 50 preferably made of a number of layers of fabric which are cemented together and are molded into the form desired, the layers being treated with some compound which will stiffen or harden them. The head is 55 constructed as shown in Figs. 2, 3 and 6, being made in two sections, each section being a

shell 5, and the two sections fitting together with their edges abutting in a vertical plane passing through the head just back of the ears. Each such shell-like portion of the head is made of a plurality of layers of fabric as indicated in Fig. 6, these layers being properly molded and being stiffened by treatment with some hardening solution. Each section is covered with a waterproofed 65 cloth 20, which is attached to the layers of fabric by some cementitious material, these coverings having edges 21 which abut on the same plane as the edges of the fabric layers. These abutting edges are held together by 70 a strip 40 of stiffened fabric layers which is positioned as shown in Fig. 6 and cemented or glued to the head sections, thus covering this joint. The two ears 6 are formed integrally with the front section and are relatively flexible, these ears overlapping the abutting edges of the two sections. 75

The two sections of the head when thus connected are provided at the bottom with a single reinforcing plate or disk 7 which is 80 attached to the sides of the head sections and is of a size adapting it to fit snugly within the recess 4 in the plate 3. On opposite sides of the plates 3 and 7, there are placed metal disks or washers 8, and 85 through these washers and the plates 3 and 7 there is passed a bolt or other suitable means for pivotally connecting the head to the trunk. The plate 7 is constructed in the same manner as the plate 3, that is, it is 90 built up of a number of layers of impregnated and stiffened material which are cemented together, thus providing a firm support for the head on the trunk.

Referring now to Figs. 2 and 4, there will 95 be seen to be a cylindrical casing 9 extending between each two limbs, this casing being constructed of the same material as the outside covering of the body. Each pair of limbs are set into this casing, each limb comprising a limb proper 10, which is provided with a cylindrical extension 11 which is pivotally received within the casing 9 and is provided at the inner end with a reinforcing plate 12. The two extensions 11 are 100 of sufficient length to fill the entire casing 9, the reinforcing plates 12 then abutting against each other and being pivotally attached to each other by suitable means such as a bolt 13 passing through these plates 110 which are backed up by metal disks or washers 14. The two limbs are thus

2

pivottally secured together and are firmly held in attachment with the trunk, although this attachment is of such a nature that strain on the limb will not tend to tear the same from the trunk as is the case where the limb is attached directly to the trunk by sewing the cover fabrics of the two together. The plates 12 are constructed in the same manner as the plates 3 and 7, that is they are made up of a number of layers of fabric which are impregnated with a suitable solution to harden them, these layers then being cemented together. By reason of this method of attachment of the lower limbs to the trunk, they are capable of movement in a substantially vertical plane, and while the upper limbs are not so attached, they are so formed that they also may move in a substantially vertical plane.

20 The present doll is extremely simple to construct and relatively inexpensive, while all movable parts, such as the arms, legs and head, are firmly secured to the trunk in such a way that they can be moved freely but cannot be torn away except by a very unusual strain. Finally, all parts of the body are covered by a waterproofed material, thus permitting the doll to be washed, while the head is practically indestructible, being made up of a large number of cemented, thin layers which are molded to shape and hardened.

Other modes of applying the principle of my invention may be employed instead of the one explained, change being made as regards the mechanism herein disclosed, provided the means stated by any of the following claims or the equivalent of such stated means be employed.

40 I therefore particularly point out and distinctly claim as my invention:—

1. In a toy figure, the combination of a body provided at the top of the trunk with a reinforcing plate having a recess therein, and a head set into such recess and pivotally attached to said plate.

2. In a toy figure, the combination of a body provided at the top of the trunk with a reinforcing plate having a recess therein, and a head provided with a transverse bottom plate set in such recess in said reinforcing plate and pivotally attached thereto.

3. In a toy figure, the combination of a body provided at the top of the trunk with an internal reinforcing plate of hardened fabric having a circular shallow recess

therein, a head provided with a transverse bottom plate of hardened fabric set in such recess, metal washers disposed on opposite sides of said plates, and a bolt passing centrally through said plates and washers and pivotally connecting said head and body.

4. In a head for a doll, the combination of front and back shell portions with edges abutting in a transverse vertical plane directly behind the ears, the front shell portion having ears formed integral therewith and overlapping the back portion.

5. In a toy figure, the combination of a trunk having a cylindrical casing extending therethrough, limbs set into opposite ends of said casing and provided with transverse plates at the inner end, and means connecting said plates.

6. In a toy figure, the combination of a trunk having a cylindrical casing extending therethrough, limbs set into opposite ends of said casing and provided with transverse plates at the inner end, and means pivotally connecting said plates.

7. In a toy figure, the combination of a trunk having a cylindrical casing extending therethrough, limbs, each having an extension adapted to fit snugly into such casing and terminating in a transverse plate and means for pivotally connecting such plates, thereby pivotally attaching such limbs together.

8. In a toy figure, the combination of a trunk having a cylindrical casing extending therethrough, limbs, each having an extension attached at an angle to the limb proper and adapted to fit snugly into such casing, each such extension terminating in a transverse plate at substantially the center of such casing, and means for pivotally connecting such plates, thereby pivotally attaching such limbs together.

9. A doll comprising a waterproof trunk without an opening thereinto, but with an inclosed passage approximately cylindrical therethrough, and a pair of water-proof limbs each having an extension fitting snugly in such passage and such extensions being pivotally connected within such passage.

Signed by me, this 4th day of September, 1915.

LOULA S. REEVES.
